ELECTRIC SEPARATING FILTER

Walter Will, Berlin-Charlottenburg, Germany,
assignor to C. Lorenz Aktiengesellschaft, Berlin-Tempelhof, Germany, a company

Application November 2, 1937, Serial No. 172,353
In Germany November 3, 1936

1 Claim. (Cl. 178—44)

The present invention relates to electric separating filters.

The wire-radio intelligence transmission over telephone and other networks by means of alternating high frequency carrier currents for broadcasting, alarm signaling and similar purposes is well known. Electric separating filters must thereby be provided which are adapted to separate the transmitted low frequency currents, 10 for instance telephone speech currents, from the high frequency currents simultaneously transmitted over the network. It has been proposed to provide the inductances of such electric separating filters with shell-shaped high-frequency 15 iron cores and to place said inductances on a shaft common thereto. It has also been proposed to assemble the inductances of the high-frequency filter portion on one shaft, and those of the low-frequency filter portion on a second 20 shaft, and to combine these two assemblies together with the necessary condensers in one structural unit. Such type of separating filters having high-frequency and low-frequency portions is preferably employed in the subscribers' 25 stations in order to discriminate between the high-frequency and the low-frequency wire-radio currents.

The present invention has for its object to provide a particularly useful design for this type 30 of electric separating filters.

According to the invention, all elements of the separating filter device are so mounted on a base plate, preferably of moulded insulating material, as to secure easy exchangeability of the individual elements and economical manufacturing 35 of the filtering device as a whole.

The invention will be more readily understood from the following description in conjunction with the attached drawing, in which—

40 Fig. 1 shows a partially sectioned front elevation of one embodiment according to the invention, while

Fig. 2 illustrates a section through the line 2—2 of the representation of Fig. 1.

45 Referring to the drawing, a base plate 1, preferably of moulded insulating material, carries terminal screws 2 which serve for establishing connections to the wire-radio lines as well as to the subscribers' telephone sets. A box-shaped container 4, enclosing the condensers of the high-frequency and the low-frequency portions of the separating filter, is carried by a rib 3 of the base plate 1. The base plate 5 of the container 4 is attached to the rib 3 by screws 6. The inductances 23, 13 and 14 of the low-frequency portion

are placed on a spindle 7 common thereto, on which they are clamped together by a nut 24. The end of the spindle opposite to the nut 24 is formed to a stop head 27. The spindle is supported by arms 8 of the base plate 1, preferably integral therewith. Each of the inductances 23, 13 and 14 comprises a coil 9 (or 9a in the case of inductance 23), an inner cylinder 10 (or 10a in the case of inductance 23), an outer cylinder 11 (or 11a for inductance 23) and two facing 10 discs 12. The coil 9a of the inductance 23 is provided with two windings. The facing discs 12 as well as the cylinders 10, 10a, 11 and 11a, which together form shell-shaped cores, consist 15 of high-frequency iron.

The inductance assembly of the high-frequency portion comprises one high-frequency transformer 15 and two inductances 16 and 17. These inductances 15, 16 and 17, and a number of the condensers enclosed in the container 4, are interconnected to a condenser circuit. Said inductances are mounted on a spindle 18 and formed similar to the inductances 23, 13 and 14 the principal difference being that their windings 9', 9' and 9a' are designed for high frequencies. Their remaining structural members, therefore, are provided with the corresponding reference numerals 10, 11, 12, 10a, 11a', 12' and 21', the primed references 11a', 12' and 21' referring to members which have larger diameters than 30 the members represented by the corresponding unprimed references 11a, 12 and 21. Also the inductances 15, 16 and 17 are supported by arms 8 of the base plate 1 and clamped together on the spindle 18 by a nut 25. The end of the spindle 18 opposing said nut is provided with a stop head 28. Between the inductances 23, 13 and the inductances 17, 15, or in any other suitable position an insulating plate or disc 21 is provided on each of the spindles 7 and 18. Each 40 disc 21 has soldering tabs 22, to which the lead-in conductors 20 are connected. A protecting cover 19 is attached to the base plate 1, and may be slid thereto on a frame-shaped ledge, for example. The leads 20 inter-connecting the individual elements of the filter device are shown merely in the Fig. 2 for the sake of simplicity. For the same reason, also the cover 19 has been 45 illustrated in the Fig. 2 only.

The electric separating filter above described 50 is preferably used in the subscribers' telephone equipment. The telephone set and one or more receiving apparatus adapted to receive the wire-radio transmission are associated with the electric separating filter.

What is claimed is:

An electric separating filter of the type having a high-pass branch and a low-pass branch which comprises a plurality of high frequency inductances for said high-pass branch and a plurality of low frequency inductances for said low-pass branch, at least two of said inductances being mutually coupled together and at least two others of said inductances being substantially free from mutual coupling, a common shell-type core structure of high frequency iron linking through and surrounding said two mutually coupled inductances, individual shell-type core structures of high frequency iron linking through and surrounding each of said coupling-free inductances,

a spindle passing through and supporting all said high frequency inductances, a second spindle passing through and supporting all said low frequency inductances, a plurality of condensers, a housing can containing all said condensers, 5 electrical connections joining said inductances and said condensers to constitute a separating filter circuit, a base plate, and means for supporting said two spindles remote from one another on said base plate and for supporting said 10 housing can on said base plate in an intermediate position between said high frequency and low frequency inductances.
